UNITED STATES PATENT OFFICE.

GEORGE K. GUINZBURG, OF NEW YORK, N. Y., ASSIGNOR TO I. B. KLEINERT RUBBER COMPANY, A CORPORATION OF NEW YORK.

DESIGN FOR A GARMENT PROTECTOR.

60,188.

Specification for Design.

Patented Jan. 10, 1922.

Application filed July 2, 1920. Serial No. 393,719. Term of patent 14 years.

To all whom it may concern:

Be it known that I, GEORGE K. GUINZBURG, a citizen of the United States, residing in the city, county, and State of New York, have invented a new, original, and ornamental Design for Garment Protectors, of which the following is a specification, reference being had to the accompanying drawing, forming part hereof, in which—

Figure 2 is a side elevation of the same. A feature of the design resides in the smooth and substantially tubular bindings which enclose the Shirred margins of the garment adjacent to the leg openings and the waist opening.

I claim:

The ornamental design for a garment protector, as shown and described.

GEORGE K. GUINZBURG.
